UNITED STATES PATENT OFFICE.

WILLIAM F. DURYEA, OF HACKENSACK, NEW JERSEY.

DESIGN FOR A PEN OR PENCIL RETAINER.

No. 40,082.

Specification for Design.

Patented June 22, 1909.

Application filed March 31, 1909. Serial No. 487,103. Term of patent 3½ years.

To all whom it may concern:

Be it known that I, WILLIAM F. DURYEA, a citizen of the United States, and a resident of Hackensack, in the county of Bergen, State of New Jersey, have invented a new, original, and ornamental Design for a Pen or Pencil Retainer, of which the following is a specification, reference being had to the accompanying drawings, forming a part thereof, wherein—

I claim—

The ornamental design for a pen or pencil retainer, substantially as shown.

WM. F. DURYEA.
